US00D844616S

(12) **United States Design Patent** (10) **Patent No.:** **US D844,616 S**
Castle et al. (45) **Date of Patent:** **** Apr. 2, 2019**

(54) **WIRELESS KEYPAD**

(71) Applicant: **Robert Bosch GmbH**, Stuttgart (DE)

(72) Inventors: **Scott Castle**, Fairport, NY (US); **Nick Billow**, Pittsford, NY (US); **Eric Harnischfeger**, Penn Yan, NY (US); **James Thornton**, Webster, NY (US)

(73) Assignee: **Robert Bosch GmbH**, Stuttgart (DE)

(**) Term: **15 Years**

(21) Appl. No.: **29/654,885**

(22) Filed: **Jun. 28, 2018**

Related U.S. Application Data

(62) Division of application No. 29/572,122, filed on Jul. 25, 2016, now Pat. No. Des. 825,564.

(57) **CLAIM**

The ornamental design for a wireless keypad, as shown and described.

DESCRIPTION

FIG. 1 is a perspective view of a wireless keypad;

FIG. 2 is a front view thereof;

FIG. 3 is a back view thereof;

FIG. 4 is a right side view thereof;

FIG. 5 is a left side view thereof;

FIG. 6 is a top view thereof; and,

(Continued)

FIG. 7 is a bottom view thereof.

The broken lines in the drawings depict portions of the wireless keypad that form no part of the claim.

1 Claim, 5 Drawing Sheets
